THREAD HOLDER OPERATED BY
LOOM VIBRATION

Herbert A. Whitin, Worcester, Mass., assignor to
Crompton & Knowles Loom Works, Worcester,
Mass., a corporation of Massachusetts

Application March 14, 1944, Serial No. 526,369

12 Claims. (Cl. 139—247)

This invention relates to improvements in thread holders for weft replenishing looms more particularly of the type employing thread engaging geared members which are actuated by a vibrator motor and it is the general object of the invention to provide means by which the loom vibration can be utilized to better advantage for turning the geared members.

In Payne Patent No. 1,842,731 there is set forth a thread holder having geared members mounted on a casing which contains a vibration motor connected to the members. As the casing swings back and forth on its supporting arm due to loom vibration a weight suspended for free oscillation moves a feed pawl relatively to a ratchet wheel connected to at least one of the geared members for the purpose of turning the latter. Such a thread holder depends for its operation upon the degree to which the casing will respond to loom vibration.

When the casing which holds the geared members and the ratchet wheel has considerable weight it does not respond sufficiently to loom vibration to operate the aforesaid weight. It is an important object of my present invention to provide means external to the casing and so constructed as to vibrate freely during loom operation without regard to the degree of vibration or absence of it on the part of the casing.

The casing is ordinarily supported by an arm secured to one of the tie rods of the reserve bobbin magazine and it is a further object of my present invention to secure a thin strip of resilient material, such as sheet steel, to the arm for the purpose of supporting and actuating the feed pawl. The magazine and the upper part of the arm secured thereto vibrate in usual manner and actuation of the strip of sheet steel material is derived from this vibration.

It is a further object of my present invention to provide a thread holder unit comprising two joined arms one of which is resilient with one end carrying a feed pawl which is movable with respect to the other arm for the purpose of actuating a ratchet wheel mounted on said other arm.

It is a further object of my invention to provide means for varying the period of vibration of the resilient arm, as by a dampener weight adjustable along the length of the arm.

With these and other objects in view which will appear as the description proceeds, my invention resides in the combination and arrangement of parts hereinafter described and set forth.

In the accompanying drawing, wherein a con-

venient embodiment of my invention is set forth,

Fig. 1 is a front elevation of a portion of a loom having my improved thread holder applied thereto,

5 Fig. 2 is an enlarged side elevation looking in the direction of arrow 2, Fig. 1,

Fig. 3 is a view looking in the direction of arrow 3, Fig. 1 on an enlarged scale and showing the interior of the casing and the parts located

10 therein, and

Fig. 4 is a rear elevation looking in the direction of arrow 4, Fig. 2.

Referring particularly to Fig. 1, I have shown a loom frame 10, a lay 11 and picking mechanism 15 12 for shuttle S. The latter moves back and forth across the lay and comes to rest periodically under a magazine M having reserve bobbins B therein from which extend weft ends W. A rigid arm 13 is secured as at 14 to one of the tie rods 15 of the magazine and extends diagonally behind the magazine. A thread holder designated generally at H is mounted on the lower end of arm 13 and is provided with front and back thread engaging geared members 16 and 17, respectively, mounted on shafts 18 and 19, respectively. As shown in Fig. 3 the shaft 18 has a ratchet wheel 20 secured thereto, while the other shaft 19 is mounted on an arm 21 pivoted at 22 with respect to the holder. A spring 23 is 20 located between arm 21 and another arm 24 adjustable horizontally on a threaded rod 25 rotatable in the upper part of the thread holder and having a thumb nut 26 by means of which the arm 24 may be moved toward and from the arm 21 for the purpose of varying the force exerted by spring 23.

30 The matter thus far described is of common construction and may be set forth as in the aforesaid patent to Payne and also in my co-pending application Serial No. 518,702, filed January 18, 1944.

In order that the ratchet wheel 20 may be actuated, I provide an auxiliary arm 30 made 45 preferably of resilient material such as sheet steel and secure the upper end thereof to arm 13 as at 31. The lower end of the auxiliary arm 30, spaced from and movable relatively to arm 13, has extending therethrough a rod 32 adjustable transversely and held in adjusted position by lock nuts 33. A resilient pawl 34 is held as at 35 to the rod 32 and extends through a slot 36 formed in wall 37 of the holder and engages the ratchet wheel.

50 In order that the period of vibration of arm 30 may be regulated I use a dampener 40 held

adjustably along the length of the auxiliary arm by means of a set screw 41. By changing the distance between the dampener and the attaching means 31 I am able to alter the rate of vibration of the auxiliary arm and adapt the feed of the ratchet wheel to changing conditions.

During loom operation there is sufficient vibration of the magazine M to cause movement of the upper part of arm 13 and also of the attaching means 31. This vibration is communicated to the auxiliary arm 30 and the lower or free end of the latter therefore swings back and forth in a direction toward and from the casing H. When the pawl moves inwardly or to the right as viewed in Fig. 3 it has a feeding stroke with respect to the ratchet wheel 20, and when the pawl moves to the left it has an idle stroke in preparation for the ensuing working stroke. There may be some slight vibration of the holder H but this will be insufficient of itself to cause appreciable movement of the ratchet wheel toward and from arm 30.

If the pawl is feeding too rapidly the weighted dampener 40 may be moved outwardly or toward the pawl end of the auxiliary arm, and in converse manner if the pawl is not feeding fast enough the dampener weight can then be moved upwardly toward the attachment 31.

From the foregoing it will be seen that I have provided simple means for operating the ratchet of a geared thread holder by means of an auxiliary resilient arm vibrating independently of the holding H. The latter may therefore be made with considerable weight such as will hold it substantially stationary during loom operation, and vibration of resilient arm 30 can be relied upon to operate the pawl and ratchet. It will furthermore be seen that the dampener 40 provides means for varying the feed of the ratchet wheel 20 by the pawl 34.

Having thus described my invention it will be seen that changes and modifications may be made therein by those skilled in the art without departing from the spirit and scope of the invention and I do not wish to be limited to the details herein disclosed, but what I claim is:

1. In a thread holder having geared members for the weft ends of a weft replenishing loom, a support arm connected at one end to the loom, a ratchet wheel connected to one of said geared members, a carrier for the ratchet wheel and geared members mounted on said arm and remaining in a substantially fixed position during loom operation, an auxiliary arm on the support arm vibrating relatively to said carrier during loom operation, and a drive pawl for the ratchet wheel mounted on and moving with the auxiliary arm when the latter vibrates.

2. In a thread holder having geared members for the weft ends of a weft replenishing loom, a support arm connected at one end to the loom, a ratchet wheel connected to one of said geared members, a carrier for the ratchet wheel and geared members mounted on said arm and remaining in a substantially fixed position during loom operation, a resilient arm mounted on the support arm and vibrating relatively to the carrier during loom operation, and a pawl on the resilient arm moving with the resilient arm and driving the ratchet wheel during loom operation.

3. In a thread holder having a casing supporting geared members for the weft ends of a weft replenishing loom, a ratchet wheel within the casing operatively connected to one of said members, a loom supported arm on which the casing

is mounted, said casing remaining in substantially fixed position during loom operation, an auxiliary arm on the loom supported arm vibrating during loom operation, and a pawl on the auxiliary arm projecting from the latter into the casing and operatively related to said ratchet wheel to turn the latter when the auxiliary arm vibrates.

4. In a thread holder having a casing supporting geared members for the weft ends of a weft replenishing loom, a ratchet wheel within the casing operatively connected to one of said members, a loom supported arm on which the casing is mounted, said casing remaining in substantially fixed position during loom operation, a resilient element mounted on said arm and having a free end which vibrates relatively to said casing during loom operation, and a pawl carried by said free end of said element and projecting into said casing into driving relation with said ratchet wheel to turn the latter when said member vibrates due to loom operation.

5. In a thread holder having geared members for the weft ends of a weft replenishing loom, two joined elements deriving support from the loom, a casing mounted on one of said elements and supporting said geared members, a ratchet wheel operatively connected to one of said geared members and supported by said casing, and a pawl on the other element projecting into said casing and engaging said ratchet wheel, said other element vibrating relatively to said casing during loom operation and causing said pawl to rotate said ratchet wheel.

6. A thread holder unit for the weft ends of a weft replenishing loom, said unit comprising a rigid arm having provision for attachment to the loom, weft end engaging geared members, a ratchet wheel operatively connected to one of said geared members, said members and wheel deriving support from said rigid arm, a resilient element mounted on said rigid arm and having a free end movable relatively to said ratchet wheel, and a pawl on said element operatively related to said ratchet wheel.

7. A thread holder unit for the weft ends of a weft replenishing loom, said unit comprising a rigid arm having provision for attachment to the loom, a casing secured to said arm, geared weft end engaging members rotatable on said casing, a ratchet wheel operatively connected to one of said geared members and supported by said casing, a resilient element supported by said arm and having a part thereof movable relatively to the casing, and a pawl on said part of said element extending into the casing and having driving relation with said ratchet wheel.

8. A thread holder unit for the weft ends of a weft replenishing loom, said unit comprising two joined elements one of which is rigid and has provision for attachment to the loom and the other element of which is resilient and has a part movable relatively to the rigid element, weft end engaging geared members rotatable on said rigid element, a ratchet wheel rotatable on said rigid element and operatively connected to one of said geared members, and a pawl on said part of the resilient element engaging said ratchet wheel.

9. In a threaded holder having geared members for the weft ends of a weft replenishing loom, a support arm connected at one end to the loom, a ratchet wheel connected to one of said geared members, a carrier for the ratchet wheel and geared members mounted on said arm and remaining in a substantially fixed position during

loom operation, a resilient arm mounted on the support arm and vibrating relatively to the carrier during loom operation, a pawl on the resilient arm moving with the resilient arm and driving the ratchet wheel during loom operation, and a weighted member held in adjusted position along said resilient arm to determine the period of vibration thereof.

10. In a thread holder having a casing supporting geared members for the weft ends of a weft replenishing loom, a ratchet wheel within the casing operatively connected to one of said members, a loom supported arm on which the casing is mounted, said casing remaining in substantially fixed position during loom operation, an auxiliary arm for the loom supported arm, connecting means between said loom supported arm and one end of said auxiliary arm, the latter vibrating during loom operation, a pawl on the auxiliary arm projecting from the latter into the casing and operatively related to said ratchet wheel to turn the latter when the auxiliary arm vibrates, and a dampener on said auxiliary arm movable to different distances from said connecting means to vary the period of vibration of said auxiliary arm.

11. A thread holder unit for the weft ends of a weft replenishing loom, said unit comprising a

5 rigid arm having provision for attachment to the loom, weft end engaging geared members, a ratchet wheel operatively connected to one of said geared members, said members and wheel deriving support from said rigid arm, a resilient element mounted on said rigid arm and having a free end movable relatively to said ratchet wheel, a pawl on said element operatively related to said ratchet wheel, and a dampener movable to different positions on said resilient element to vary the period of vibration thereof.

10. A thread holder unit for the weft ends of a weft replenishing loom, said unit comprising two joined elements one of which is rigid and has provision for attachment to the loom and the other element of which is resilient and has a part movable relatively to the rigid element, weft end engaging geared members rotatable on said rigid element, a ratchet wheel rotatable on said rigid element and operatively connected to one of said geared members, a pawl on said part of the resilient element engaging said ratchet wheel, and a dampener on said resilient element movable to different distances from the point of 15 joining of said elements to vary the period of vibration of said resilient element.
